FLEXIBLE DRINKING STRAW

William Nardone, Revere, Mass., assignor to Sweetheart
Plastics, Inc., Wilmington, Mass., a corporation of Maryland

Filed May 18, 1967, Ser. No. 7,174

Term of patent 14 years

(Cl. D94—3)

FIG. 1

FIG. 2

FIG. 3

FIG. 5

FIG. 1 is a front view of the flexible drinking straw;
FIG. 2 is a left side view thereof;
FIG. 3 is a right side view thereof;
FIG. 4 is a rear view thereof; and
FIG. 5 is a top view thereof.

The broken-away portions of the drinking straw indicate indeterminate length.

I claim:

The ornamental design for a flexible drinking straw,
as shown and described.
